BEVERAGE DISPENSING VALVE

Frank R. Hessler, Kirkwood, Mo., assignor, by
mesne assignments, to The Bastian-Blessing
Company, Chicago, Ill., a corporation of Illinois

Application October 8, 1947, Serial No. 778,653

10 Claims. (Cl. 277—3)

1

This invention relates in general to certain new and useful improvements in beverage dispensing equipment.

It is the primary object of the present invention to provide a beverage dispensing valve which is capable of being adjusted while in operative condition whereby the rates of flow of carbonated water and syrup may be independently predetermined.

It is a further object of the present invention to provide a beverage dispensing valve which is provided with reliable and easily manipulated operating means.

It is an additional object of the present invention to provide a beverage dispensing valve which is provided with means to prevent flavoring syrup from seeping into the operating means and interfering therewith.

It is also an object of the present invention to provide a carbonated beverage dispensing valve which is simple and compact in construction and which can be readily attached to any existing beverage dispensing system.

It is a further object of the present invention to provide a valve of the type stated which is capable of optionally dispensing a properly proportioned flavored carbonated drink or unflavored carbonated water, as desired.

It is an additional object of the present invention to provide a valve of the type stated which is capable of dispensing carbonated water without appreciable loss of gaseous carbon dioxide, thereby supplying a carbonated drink having an unusually high degree of retained carbonation.

It is also an object of the present invention to provide a valve of the type stated which can be precisely adjusted to throttle the flow of carbonated water at any desired rate within substantially broad limits.

It is likewise an object of the present invention to provide a valve of the type stated which can be readily and quickly dismantled and reassembled for replacement of washer and any other similar parts.

With the above and other objects in view, my invention resides in the novel features of form, construction, and arrangement and combination of parts presently described and pointed out in the claims.

In the accompanying drawing—

Figure 1 is a fragmentary front elevational view of an under-bar dispenser constructed in accordance with and embodying the present invention;

Figure 2 is an enlarged sectional view of the dispensing valve of the present invention showing the valve in closed position;

2

Figure 3 is a fragmental sectional view of the dispensing valve in open position;

Figure 4 is a transverse sectional view taken along line 4—4 of Figure 2;

Figure 5 is a transverse sectional view taken along line 5—5 of Figure 3;

Figure 6 is an enlarged fragmental sectional view of the lower end of the nozzle; and

Figure 7 is a transverse sectional view taken along line 7—7 of Figure 5.

Referring now in more detail and by reference characters to the drawing which illustrates a preferred embodiment of the present invention, A designates an under-bar dispenser having a syrup pan 1 suitably fixed to the underside of a bar counter (not shown). In the bottom wall 2 of said syrup pan 1 there is provided a circular syrup discharge aperture 3 and, preferably, though not necessarily, disposed upon the upper face of the bottom wall 2 around said aperture 3 is a disk 4 having an aperture coincident with the aperture 3 and being integrally provided at uniformly spaced intervals around its periphery with upstanding resilient prongs 5 for releasably retaining a cylindrical foraminous cap or strainer 6 having a handle 6' soldered upon its upper end wall. The bottom wall 2 and disk 4, respectively, are provided with three equally spaced registering apertures 7 and 7' for receiving button-headed screws which extend therethrough, and through an elliptical gasket 9 upon the underface of the bottom wall 2 for threaded engagement in the upper end of a stainless steel cylindrical valve body 10 having an angular end face 11 for seated engagement against the gasket 9 and arranged to extend forwardly and downwardly from the forward end of the pan 1, projecting at its lower or discharge end beyond the plane of the forward end of the pan 1, as best seen in Figure 2.

Extending lengthwise upwardly into the valve body 10, is a bore 12 terminating in a lateral take-off 13 into which is welded a nipple 14, at its external or outwardly projecting end, for disengageable connection to a carbonated water line (not shown). At its lower end, the bore 12 opens upon the lower end 15 of the valve body 10, and is internally threaded to receive a stationary stainless steel nozzle-quill 16 which is conically faced off at its upper end in the provision of a valve seat-forming face 17 and is internally flared for approximately the lower half of its length to provide a discharge passage 18 having gradually increasing cross sectional area. Upon its lower end face, the nozzle-quill 16 is provided with a concentric deep groove 19 which is rounded at its top and bottom edges, as shown in Figure 6.

Slidably fitted upon, and projecting downwardly from, the nozzle-quill 16, is a tubular nozzle 20 externally provided at its upper end with a diametrically enlarged collar 21 and being at its lower end internally tapered, as at 22, to a somewhat reduced inside diameter in the provision of a constricted discharge opening 23.

Loosely and shiftably mounted within the nozzle-quill 16 is a valve stem 24 provided at its upper end with a fixed washer ring or poppet 25 and an annular downwardly presented washer 26 for seated engagement against the seating face 17. At its other end, the valve stem 24 is threadedly secured in an internally threaded longitudinal bore *a* formed in, and extending axially through, a downwardly pointed concentric cone 27 having greater angularity than the converging internal side walls of the nozzle 20 and being provided at its upper end with upwardly extending concentric or annular recesses 28 and 29 for complementary disposition, respectively, within the groove 19 and tapered passage 18 of the quill 16, as best seen in Figure 6.

Threaded in the lower end of said bore *a* of the concentric cone 27 is a set screw 32 provided with a downwardly opening recess 33 for accommodating the end of a conventional Allen wrench. The cone 27 is finally secured to the nozzle 20 by loose fitting diametrical pins 30 so that the nozzle 20, cone 27, stem 16, and washer 26, move up and down together, and the cone 27 may shift laterally on the pins 30 in a self-centering manner so that the flow through the discharge opening 23 will be even, round and concentric. The entire assembly is normally held in downwardly shifted or closed position by a compression spring 31, disposed annularly around the quill 16 and the upper end of the nozzle 20 in endwise abutment on one end against the upper face of the collar 21 and on its other end against the lower end of the face 15 of the valve body 10. By threading the set screw 32 upwardly or downwardly, the amount of threading of the bore *a* available for co-operation with the threading of the valve stem 24 may be controlled. This adjustment may be effected when the dispenser is in operating condition, obviating the necessity of dismantling. Through these means, the opening between the valve seat 17 and the washer 26, when in open position, may be controlled to insure the desired rate of flow of the carbonated water, as will be presently more fully understood.

Extending lengthwise in the valve body 10 in spaced parallel relation to the bore 12 is a second bore 34, opening at its upper end upon the upper end face 11 in registration with the syrup-drainage aperture 3. About midway of its length, the bore 34 is reduced diametrically in the provision of a shoulder 35 having a raised annular valve seat 36. Beneath the shoulder 35, the lower end of the bore 34 is increased diametrically and is internally threaded, as at *b*. Snugly fitted within the upper portion of said lower end are a plurality of rubber washers 37, tightly held against the under face of the shoulder 35 by a threaded fitting 38, having a central bore *c* and being provided on its under face with shallow drill-holes *d* for accommodating a spanner wrench or similar tool. Disposed within the lower end of the bore 34 for lengthwise shiftable, but leak-proof, movement therein and through the washers 37 is a tubular syrup-discharging spout 39 which is closed at its upper end by a transverse wall 40 centrally bored and tapped for receiving a screw 41. Held in place upon the upper end of the wall 40 by means of the screw 41 is a diametrically

enlarged disk 42 and washer 43, the latter being disposed within the enlarged upper end of the bore 34 for seated engagement against the valve seat 36. Just below its closed end, the spout 39 is provided with a plurality of radially drilled orifices 44 through which syrup may flow for ultimate discharge from the lower or open end of the spout 39 and at its lower or discharge end the spout 39 is provided with a pair of aligned shallow vertical recesses 45. In its midportion, the spout 39 is externally threaded for receiving an internally threaded set collar 46 having a locking screw 47. The spout 39 is normally held in downwardly shifted or closed position with its associated washer 43 in seated engagement against the valve seat 36 by a compression spring 48, disposed annularly therearound and abuttingly engaged at one end against the upper face of the set collar 36, and at its other end against the lower end face 15 of the valve body 10. It should be noted in this connection that the washers 37 prevent leakage of syrup around the external surfaces of the tubular spout 39 and thereby obviate the tendency of the latter to gum up and stick as the leaking syrup thickens and crystallizes, which difficulty is commonly encountered in conventional devices of this type.

Mounted by screws 49, and fitting annularly around the lower end of the valve body 10, is a sleeve 50 having a skirt 51 projecting beyond the end of the valve body 10 and being, in its lower portion, internally diametrically decreased in the provision of a narrow shoulder 52. Adjacent its lower end, the sleeve 50 is provided with two diametrically opposite circular apertures 53 for loosely accommodating therethrough a transverse bar 54. At one end of said bar 54 there is provided an upwardly and outwardly extending handle 55 having a conventional knob 56 threaded upon its outer or free end. Projecting from the lower end of the handle 55 parallel to, and adjacent, the bar 53 is a stop pin 57 extending into an aperture 58 located in the sleeve 50 eccentrically with reference to bar 54. Mounted on the transverse bar 54 within the sleeve 50 are a pair of eccentric cams 59 retained rigidly on the bar 54 and in peripheral alignment with each other by set screws 60. Loosely seated upon the shoulder 52 of the sleeve 50 is a circular plate 61 provided with an enlarged aperture 62 and a relatively smaller aperture 63 for permitting the extension therethrough of the nozzle 20 and the spout 39 respectively. Provided midway between the apertures 53 and located immediately above the shoulder 52, is an aperture 64 through which the set screw 47 may be released so that the tubular spout 39 may be turned for syrup-flow adjustment by inserting a screw driver or similar thin bladed tool in the slot 45.

In operation, the syrup pan 1 may be filled with 60 a suitable flavoring syrup such as, for example, Coca Cola syrup. The handle 55 is swung downwardly causing the cams 59 to be raised upwardly against the underface of the plate 61 driving said plate 61 upwardly off the shoulder 52. In moving upwardly, said plate 61, by abutting against the underfaces of the collars 46 and 21, causes the spout 39 and nozzle 20 to shift upwardly whereby the associated washers 43 and 26 will be moved from the closed position shown in Figure 2 to the open position shown in Figure 3. When the valve is in open position, syrup and carbonated water will flow simultaneously into a glass or other receptacle which is held thereto below and the uniformly mixed beverage will be thus made.

It should be understood that the changes and modifications in the form, construction, arrangement, and combination of the several parts of the beverage dispensing equipment may be made and substituted for those herein shown and described without departing from the nature and principle of my invention.

Having thus described my invention, what I claim and desire to secure by Letters Patent is:

1. A valve for controlling the flow of fluids comprising a valve body having a first passage extending longitudinally therethrough and being constricted intermediate its ends in the provision of a valve seat, a tubular spout slidably mounted in and projecting from one end of said first passage and being provided on its inner end with a closure element for valve-forming co-operation with the valve seat, spring means for normally urging the spout outwardly with respect to the valve body, said valve body having a second passage extending therethrough, a tubular member mounted in and projecting from one end of said second passage and being provided at its inner end with a valve seat, a stem mounted in and extending through said tubular member, a valve poppet fixed upon the upper end of said stem for co-operation with the valve seat, a discharge nozzle slidably mounted on and projecting downwardly from the tubular member and being connected to the stem for movement therewith, an abutment on the spout, an abutment on the discharge nozzle, a tubular sleeve mounted upon the valve body, the sleeve having a skirt portion which extends below the end face of the valve body, a transverse partition loosely mounted in the sleeve and apertured for loosely clearing the spout and nozzle and engaging the abutments, and handle means for shifting the transverse partition upwardly in relation to the valve body for simultaneously lifting the spout, stem and the associated closure element and poppet for opening both of said passages and permitting the flow of fluids therethrough.

2. A valve for controlling the flow of liquids comprising a valve body having a first passage extending longitudinally therethrough and being constricted intermediate its ends in the provision of a valve seat, a tubular spout slidably mounted in and projecting from one end of said first passage and being provided on its inner end with a closure element for valve-forming co-operation with the valve seat, spring means for normally urging the spout outwardly with respect to the valve body and bringing the closure element into seated engagement with the valve seat, said valve body having a second passage extending therethrough, a tubular member mounted in and projecting from one end of said second passage and being provided at its inner end with a valve seat, a stem mounted in and extending through said tubular member, a valve poppet fixed upon the upper end of said stem for co-operation with the valve seat, a discharge nozzle slidably mounted on and projecting downwardly from the tubular member and being connected to the stem for movement therewith, an abutment on the spout, an abutment on the discharge nozzle, a tubular sleeve mounted upon the valve body, said sleeve having a skirt portion which extends below the end face of the valve body, a shoulder projecting inwardly from said skirt portion, a transverse partition loosely seated upon said shoulder and apertured for loosely clearing the spout and nozzle and engaging the abutments, and handle means for shifting the

transverse partition upwardly in relation to the valve body for simultaneously lifting the spout, stem and the associated closure element and poppet for opening both of said passages permitting the flow of liquids therethrough.

3. A valve for controlling the flow of liquids comprising a valve body having a first passage extending longitudinally therethrough and being constricted intermediate its ends in the provision of a valve seat, a tubular spout slidably mounted in and projecting from one end of said first passage and being provided on its inner end with a closure element for valve-forming co-operation with the valve seat, spring means for normally urging the spout outwardly with respect to the valve body and bringing the closure element into seated engagement with the valve seat, said valve body having a second passage extending therethrough, a tubular member mounted in and projecting at its inner end with a valve seat, a stem mounted in and extending through said tubular member, a valve poppet fixed upon the upper end of said stem for co-operation with the valve seat, a discharge nozzle slidably mounted on and projecting downwardly from the tubular member and being connected to the stem for movement therewith, an abutment on the spout, an abutment on the discharge nozzle, a tubular sleeve mounted upon the valve body, said sleeve having a skirt which extends below the end face of the valve body, a shoulder projecting inwardly from said skirt, a transverse partition loosely seated upon said shoulder and apertured for loosely clearing the spout and nozzle and engaging the abutment, a bar loosely extending through apertures in the lower portion of said skirt, eccentric cams mounted upon said bar within said skirt, and a handle connected to said bar for raising said cams by turning the bar whereby the transverse partition is shifted upwardly in relation to the valve body for simultaneously lifting the spout, stem and the associated closure element and poppet for opening both of said passages permitting the flow of liquids therethrough.

4. A valve for controlling the flow of liquids comprising a valve body having a first passage extending longitudinally therethrough and being constricted intermediate its ends in the provision of a valve seat, a tubular spout slidably mounted in and projecting from one end with a closure element for valve-forming co-operation with the valve seat, spring means for normally urging the spout outwardly with respect to the valve body and bringing the closure element into seated engagement with the valve seat, said valve body having a second passage extending therethrough, a tubular member mounted in and projecting from one end of said second passage and being provided at its inner end with a valve seat, a stem mounted in and extending through said tubular member, a valve poppet fixed upon the upper end of said stem for co-operation with the valve seat, a discharge nozzle slidably mounted on and projecting downwardly from the tubular member and being connected to the stem for movement therewith, an abutment on the spout, an abutment on the discharge nozzle, a tubular sleeve mounted upon the valve body, said sleeve having a skirt portion which extends below the end face of the valve body, a shoulder projecting inwardly from said skirt portion, a transverse partition loosely seated upon said shoulder and apertured for loosely clearing the spout and nozzle and engaging the abutment, a

bar extending loosely through apertures in the lower portion of said skirt portion and across said skirt, cams mounted upon said bar, a handle connected to said bar, and a projection extending from said handle parallel to the bar into an eccentric aperture in the skirt whereby the movement of the handle is limited.

5. A valve for controlling the flow of liquids comprising a valve body having a first passage extending longitudinally therethrough and being constricted intermediate its ends in the provision of a shoulder, a valve seat mounted upon said shoulder, washers tightly held against the underside of said shoulder, a tubular spout slidably mounted in and projecting from one end of said passage and being provided on its inner end with a closure element for valve-forming co-operation with the valve seat, spring means for normally urging the spout outwardly with respect to the valve body and bringing the closure element into seated engagement with the valve seat, said valve body having a second passage extending therethrough, a tubular member mounted in and projecting from one end of said second passage and being provided at its inner end with a valve seat, a stem mounted in and extending through said tubular member, a valve poppet fixed upon the upper end of said stem for co-operation with the valve seat, a discharge nozzle slidably mounted on and projecting downwardly from the tubular member and being connected to the stem for movement therewith, an abutment on the spout, an abutment on the discharge nozzle, a tubular sleeve mounted upon the valve body and provided with a skirt extending below the lower end of the valve body, a transverse partition loosely mounted in the sleeve and apertured for loosely clearing the spout and nozzle and engaging the abutments, and handle means for shifting the transverse partition upwardly in relation to the valve body for simultaneously lifting the spout, stem and the associated closure element and poppet for opening both of said passages and permitting the flow of liquids therethrough.

6. A valve for controlling the flow of liquids comprising a valve body having a first passage extending longitudinally therethrough and being constricted intermediate its ends in the provision of a valve seat, a tubular spout slidably mounted in and projecting from one end of said first passage and being provided on its inner end with a closure element for valve-forming co-operation with the valve seat, spring means for normally urging the spout outwardly with respect to the valve body and bringing the closure element into seated engagement with the valve seat, said valve body having a second passage extending therethrough, a tubular member mounted in and projecting from one end of said second passage and being provided at its inner end with a valve seat, a stem mounted at its inner end with a valve seat, a stem mounted in and extending through said tubular member, a valve poppet fixed upon the upper end of said stem for co-operation with the valve seat, a discharge nozzle slidably mounted on and projecting downwardly from the tubular member and having an internally threaded bore for receiving the lower end of said stem, being thereby connected for movement therewith, a screw provided with a downwardly opening recess secured in the lower end of the bore, an abutment on the spout, an abutment on the discharge nozzle, a tubular sleeve mounted upon the lower end of the valve body

having a skirt extending below said valve body, a transverse partition loosely mounted in the sleeve and apertured for loosely clearing the spout and nozzle and engaging the abutment, and handle means for shifting the transverse partition upwardly in relation to the valve body for simultaneously lifting the spout, stem and the associated closure element and poppet for opening both of said passages permitting the flow of liquids therethrough.

5. A valve for controlling the flow of fluids comprising a valve body having a passage extending therethrough and being constricted intermediate its ends in the provision of a valve seat, a tubular spout slidably mounted in and projecting from one end of said passage and being provided on its inner end with a closure element for valve-forming cooperation with the valve seat, spring means for normally urging the spout outwardly with respect to the valve body, an abutment on the spout, a tubular sleeve mounted upon the valve body, the sleeve having a skirt portion which extends below the end face of the valve body, a transverse partition loosely mounted in the sleeve and apertured for loosely clearing the spout and engaging the abutment, and handle means for shifting the transverse partition upwardly in relation to the valve body for lifting the spout and the associated closure element for opening said passage and permitting the flow of fluid therethrough.

8. A valve for controlling the flow of fluids comprising a valve body having a passage extending therethrough and being constricted intermediate its ends in the provision of a valve seat, a tubular spout slidably mounted in and projecting from one end of said passage and being provided on its inner end with a closure element for valve-forming cooperation with the valve seat, spring means for normally urging the spout outwardly with respect to the valve body, an abutment on the spout, a tubular sleeve mounted upon the valve body, the sleeve having a skirt portion which extends below the end face of the valve body, a shoulder projecting inwardly from said skirt portion, a transverse partition loosely seated upon said shoulder and apertured for loosely clearing the spout and engaging the abutment, and handle means for shifting the transverse partition upwardly in relation to the valve body for lifting the spout and the associated closure element for opening said passage permitting the flow of liquid therethrough.

9. A valve for controlling the flow of fluids comprising a valve body having a passage extending therethrough and being constricted intermediate its ends in the provision of a valve seat, a tubular spout slidably mounted in and projecting from one end of said passage and being provided on its inner end with a closure element for valve-forming cooperation with the valve seat, spring means for normally urging the spout outwardly with respect to the valve body, an abutment on the spout, a tubular sleeve mounted upon the valve body, the sleeve having a skirt portion which extends below the end face of the valve body, a shoulder projecting inwardly from said skirt, a transverse partition loosely seated upon said shoulder and apertured for loosely clearing the spout and engaging the abutment, a bar loosely extending through apertures in the lower portion of said skirt, eccentric cams mounted upon said bar within said skirt, and a handle connected to said bar for raising said cams by turning the bar whereby the transverse

partition is shifted upwardly in relation to the valve body for lifting the spout and associated closure element for opening said passage and permitting the flow of liquid therethrough.

10. A valve for controlling the flow of fluids comprising a valve body having a passage extending therethrough and being constricted intermediate its ends in the provision of a valve seat, a tubular spout slidably mounted in and projecting from one end of said passage and being provided on its inner end with a closure element for valve-forming cooperation with the valve seat, spring means for normally urging the spout outwardly with respect to the valve body, an abutment on the spout, a tubular sleeve mounted upon the valve body, the sleeve having a skirt portion which extends below the end face of the valve body, a shoulder projecting inwardly from said skirt portion, a transverse partition loosely seated upon said shoulder and apertured for loosely clearing the spout and engaging the abutment, a bar extending loosely through apertures in the lower portion of said skirt portion and across said skirt, cams mounted upon said bar, a handle connected to said bar, and a projection extending from said handle parallel to the bar into an eccentric aperture in the skirt whereby the movement of the handle is limited.
